Schechter & Schecter

UNITED STATES PATENT OFFICE.

FRANCIS X. MALOCSAY, OF UPPER SADDLE RIVER, NEW JERSEY, ASSIGNOR TO INTERNATIONAL BANDING MACHINE COMPANY, A CORPORATION OF NEW YORK.

ADJUSTING MECHANISM.

Application filed May 21, 1923. Serial No. 640,464.

This invention relates to machines in which a plurality of articles are fed one at a time to a predetermined feeding position and thereafter are transferred automatically from said feeding position to operating position, where the articles are acted upon by a second machine. More particularly this invention relates to combined cigar feeding and banding machines in which a plurality of cigars are adapted to be fed automatically one at a time to feeding position and then transferred by automatic means to banding position where the banding machine operates upon them to apply a band.

It will be understood that the mechanism which moves the cigars from feeding position to banding position operates through a predetermined distance each time. So that, if the cigar is properly gaged in feeding position, it will, when moved to banding position, be properly gaged relative to the band applying machine. It is essential that the cigar in banding position should be very accurately gaged, because any deviation from properly gaged position will cause the band to be applied irregularly or out of centralized position. The cigar, when in feeding position, is properly gaged by suitable gaging means which limit its movement toward the feeding position. In this position, the longitudinal axis of the cigar occupies a certain definite predetermined position, which may be indicated by a line which may be called B. From this position the cigar is moved to banding position, and when properly gaged in banding position, its longitudinal axis will coincide with a predetermined axis of the banding machine, which we may call A. The throw of the transferring means is such that the longitudinal axis of the cigar will be moved from B to A. If, now, a cigar of different width, for example, a much thinner cigar, replaces the thicker cigar and is gaged in feeding position against the same limit of gaging means, it will be apparent that the longitudinal axis of the thinner cigar will be somewhat removed from the position occupied by the longitudinal axis of the thick cigar. If, now, the thin cigar is moved by the transferring means to the banding position, the distance through which the longitudinal axis of the thin cigar moves is the same as the distance through which the longitudinal axis of the thick cigar moves. So that, if the axis of the thin cigar is removed from the position occupied by the axis of the thick cigar in feeding position, the axis of the thin cigar will be similarly removed from the position occupied by the axis of the thick cigar in banding position, so that, if the machine were set for the thick cigar so that the latter were in properly gaged feeding position and banding position, the thin cigar will be offset from the properly gaged feeding position and similarly offset from the properly gaged banding position, so that the band will not be properly applied.

It is one of the objects of this invention, therefore, to provide adjusting means whereby the cigar in feeding position may be adjusted corresponding to the various thicknesses of cigars, so that, regardless of the size of the cigar, it will occupy the properly centralized position when in banding or operating position. For this purpose I provide means for varying the throw of the feeding means and gaging means toward feeding position so as to bring the cigars, regardless of their thickness, always to the same predetermined feeding position. Thus, for a thinner cigar, the movement of the feeding and gaging means toward feeding position would be decreased so as to move the longitudinal axis of the cigar away from the banding position, while for a thicker cigar the movement of the feeding and gaging means toward feeding position would be increased to move the axis of the cigar nearer the banding position.

For transferring the cigars from feeding position to banding position, I employ suitable gripping means adapted to engage the cigar in feeding position and move it to banding position. This gripping means is adapted to engage the cigar substantially over its entire upper and lower surfaces. It is apparent, therefore, that if a thinner cigar were substituted for a thicker cigar, if the gripping means would extend beyond the cigar in feeding position and engage a part of the second cigar, when the gripping means is operated to banding position, there is a likelihood that more than one cigar would be moved at a time to banding position. To obviate this difficulty, therefore, it is necessary to adjust the movement of the

gripping members toward feeding position as well as to adjust the throw of the feeding and gaging means toward feeding position, whenever a cigar of different thickness 5 is inserted in the machine. Thus, for a thin cigar not only is the movement of the feeding and gaging means toward feeding position decreased, but the movement of the gripping means toward said position is also 10 decreased, because it is not necessary for said gripping means to travel quite as far to grip this thin cigar over its entire surface. Similarly, for a thicker cigar, the movement of the feeding and gaging means 15 toward feeding position is increased and the movement of the gripping means toward feeding position is similarly increased, because it is necessary for said gripping means to travel a greater distance to engage 20 the entire surface of the thicker cigar.

It is a further object of my invention to provide means for simultaneously adjusting the movement of the feeding and gaging means and the movement of the gripping 25 means, since, as we have seen, there is a definite relationship between the two in that the movement of all of said means toward feeding position is increased together or decreased together corresponding to various 30 thicknesses of cigars.

It is a further object of my invention to provide a single operating member for simultaneously adjusting both the feeding and gaging means and the gripping means. 35 By this construction, it is possible for the operator to make the necessary adjustments rapidly and efficiently.

It is a further object of my invention to provide graduated means whereby the operator can tell at a glance exactly to what 40 degree the adjustments have been made, so that the machine can be set accurately for various thicknesses of cigars.

Other objects and advantages will appear as the nature of the improvements is 45 better understood, the invention consisting substantially in the novel arrangement and co-relation of instrumentalities herein fully described and illustrated in the accompanying drawing considered together or separately and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an 55 illustrative, rather than a restrictive, standpoint.

The inventive idea involved is capable of receiving a variety of mechanical expressions, one of which, for the purposes of illustration, is shown in the accompanying draw-

ing, in which is shown a front view of my machine with parts broken away for the purpose of clarifying the structure.

The device comprises essentially a feeding mechanism for moving cigars or similar articles up to the feeding position, indicated by the line B, the gripping mechanism for transferring the cigar or other article from feeding position to banding or operating position indicated by line A, and the adjusting mechanism for adjusting both of said first named devices.

A layer of cigars 1 is adapted to be discharged from a hopper upon a table 2 in such manner that the cigars occupy the same 80 relative positions as in the cigar box when packed.

The feeding mechanism comprises a plurality of bars 3, which operate in slots cut in the table top and which are given both 85 an up-and-down and left-to-right movement. The movement is, therefore, essentially elliptic. In their upward and right movement, the bars are raised above table 2 to lift the cigars off the table and move 90 them forwardly to the right. In the lower and left movement they deposit the cigars on the table and move beneath the table out of contact with the cigars. When they reach their extreme left position they begin 95 their upward and right movement to feed the cigars forwardly again the distance of one cigar width.

Each bar 3 is provided with a downwardly extending fork 30' adapted to straddle a shaft 5 at one end of an arm 6 of a bell crank 7, pivoted in a hanger 8, fixed to the main frame of the machine. Also pivoted on the axis of shaft 5, is a gage finger 9 adapted in its extreme movement to the right to gage 100 the cigar in feeding position. The gage finger 9 is also given an up-and-down and a right-and-left movement. The gage finger is caused to lag somewhat behind the downward movement of the bars (by mechanism 105 to be hereinafter described) so as to hold the first cigar in feeding position B until the left upper and lower gripping fingers 4, 4' 110 contact with the cigar in feeding position preparatory to moving said cigar to banding 115 position A. Then the gage finger 9 is lowered out of contact with the cigar in feeding position, and the movement thereof to the left is substantially the same as that of the bars.

For the purpose of giving the bars their up-and-down movement there are provided bell cranks 12 pivoted on the fixed frame at 43, having rollers 42 at the end of one arm and having their other arms connected by link 13 to effect parallel movement 120 of said bell cranks. The bell cranks are rotated by link 14 connected to the pivot of one of them (here shown as left bell crank), the said link being connected to a link 15 125 attached at 96 to bell crank 16, pivoted at 130

17 on the main frame of the machine and operated from a cam 92 at the extreme right, said cam being continuously rotated from any suitable source of power to provide continuous rocking of said bell crank 16, and hence continuous up-and-down movement of the bars 3. That is, for each revolution of the cam the bars will make a complete up-and-down cycle. Compounded with the up-and-down movement of the bars is the forward and rearward movement which is effected by means of the bell crank 7, one arm 6 of which engages in the forks 30 on the underside of the bars, said bell crank 7 having a roller 25 in engagement with a cam 26 carried by hub 27, fixed to the extreme left end of an operating shaft 29 adapted to be reciprocated continuously. Shaft 29 is fixed at the right end in a hub 46 having rollers 47 whereby the shaft and the mechanism carried thereby is supported on rails 48 on the fixed frame of the machine. The shaft 29, together with the hub 27 and cam 26, may be reciprocated by means of a link 30 connected thereto at 31, said link being pivotally connected to a lever 94, adapted to be operated by cam 32 which rotates continuously. At the end of the movement of the cam 26 to the right, the bars 3 drop because of the action of the cam 92 and the connecting mechanism. The cam eventually moves so far to the right that gage finger 9 engages the row of cigars on the table which have sufficient resistance to prevent further downward rotation of bell crank 7. The roller 25 may at this time be some distance off the cam 26. By this arrangement, therefore, it is assured that the gage finger 9 will in every case come into contact with the next 40 cigar to be moved to feeding position. The degree of movement of the gage finger to the left is such that said finger engages the row of cigars and moves said row slightly to the left before it reaches the limit of its left movement. During the movement of cam 26 to the left, bell crank 7 is rotated to move the bars 3 and finger 9 to the right to feeding position. Not only the bars, therefore, but the finger 9 gets its right and left movement from cam 26, operated by the shaft 29. Finger 9, however, is only pivotally connected to one arm of bell crank 7 and is given a separate independent up-and-down movement, so that when the bars go down to deposit the cigars on the table top 2, the gage 50 9 still remains upward until the gripping fingers 4, 4^a engage the cigar in feeding position B. When the fingers 4, 4^a have engaged the cigar in position B, the gage 9 is drawn downward to disengage said first cigar and is moved rearwardly by bell crank 7 together with bars 3 and is later moved upwardly to engage the said cigar after having been drawn back somewhat less than 55 one cigar width. The movement to the left

continues so that gage 9 probably moves the row of cigars to the left a trifle, as described, thus ensuring engagement with the next cigar. The movement to the right is then accomplished as before by the bell crank 7, the bars being in elevated position, through the operation of links 14, 15. To give the gage finger 9 a separate up-and-down movement there is pivoted thereto at 45, intermediate the length thereof a link 33, whose other end has a universal connection 34 to a hub 35, which is operated by a bell crank 36 and cam 37, said cam being similar to cam 32, and said crank being similar to crank 16.

The operation of the feeding mechanism, 80 although apparent from the foregoing description, may be described as follows:

Assume gage finger 9 and bars 3 are in their extreme left positions. The gage finger is in engagement with the next cigar to be moved to feeding position. The bars are then moved upwardly, the finger having been raised during the stroke to the left, to lift the cigars off the table and to the right. The extreme right position of the bars and gage finger determines the feeding position of the cigars. The bars are then lowered to deposit the cigars on the table top, but the gage finger still remains elevated in engagement with the cigar in feeding position until 95 the gripping fingers 4, 4^a come into contact with the said cigar (by mechanism as hereinbefore described). Then the gage finger is lowered out of engagement with the cigar in feeding position and is moved with the bars toward the left. Near the end of its stroke toward the left, the finger 9 is elevated in front of the next cigar to be moved to feeding position. This elevation of finger 9 occurs, therefore, before the finger 100 has been moved to the left the distance of one cigar width. The total stroke to the left somewhat exceeds one cigar width, as hereinbefore described, to ensure engagement of the finger with the row of cigars. The bars 110 are then moved upwardly and to the right to feeding position, as before. The timing of the various movements depends, of course, upon the shape, size and position of the various driving cams described, and this 115 may be regulated at will to accomplish the desired results.

Also carried by the main driving shaft 29 through a link 51 is the guide or gripper block 60 connected to said link at 49 and which is slidable on the shaft 29 for the purposes of adjustment (by means to be hereinafter described), but once adjusted, moves therewith through the connection comprising the link 51 and lever 52 of the 120 adjustment. Said lever 52 is pivoted on a shaft 53 in the hub 27, the cam 26 moving integrally with said shaft and lever. Since the hub is carried on and reciprocated by shaft 29, the link 51 will be similarly actu- 125 130

ated to move the gripper block to the right as the cam moves to the right, and move it to the left as the cam moves to the left. Since, when the cam 26 moves toward the left, the feed bars 3 and gage finger 9 move toward the right, it will be obvious that the gripper block and gripper fingers carried thereby will be moved toward the left, or, in other words, in a direction opposite to the bars. That is, as the bars feed a cigar to feeding position, the gripper block and its gripping finger move toward the cigar to engage it preparatory to moving it to the banding position. It is, of course, necessary that the gripping fingers carried by the gripper block should be spread apart vertically before they engage the cigar in feeding position, so that they may come in contact with its upper and lower surfaces. For this purpose the gripper block carries upper fingers 4 which are held elevated while the gripper block is moving to the left by means of gripper bar 62 pivotally mounted at 63 on the hub 46 in which shaft 29 is fixed. Said bar 62 rests upon the upper end 65 of a link 66 within the gripper block and having engagement (by a linkage or gearing, not shown) with a slide 61 carrying the finger 4 at its upper end. As long as gripper bar 62 rests upon the upper end of said link, the finger 4 will be elevated. When the main carriage is moving toward the left to engage the cigar in feeding position B, means are provided for holding the gripper bar 62 in lowered position to keep the finger 4 elevated. The lower finger 4^a is carried upon the end of an arm 83 pivoted at 84 upon the upper end of gripper block 60 and having a pin 85 adapted to engage the upper end of block 60 to limit its downward movement. The bar 83 and fingers 4^a are adapted to rest upon gripper bar 62 to be raised and lowered as said bar is raised and lowered. So that, when gripper bar 62 is in lowered position, fingers 4 are elevated and fingers 4^a are lowered, so that these fingers may pass over and under the cigar in feeding position preparatory to grasping said cigar. When the fingers are in position over and under the cigar in feeding position, the bar 62 is adapted to be raised, thus allowing finger 4 to be lowered into engagement with the cigar and raising finger 4^a into engagement with the lower surface of the cigar. As the main carriage moves toward the right, the cigar in feeding position B will be carried to banding position A. At this point the bar 62 is adapted to be depressed again to raise fingers 4 and permit fingers 4^a to drop, thus releasing the cigar in banding position. For raising and lowering the gripper bar 62, there is provided a link 90 pivotally connected at 91 to the gripper bar 62 and connected at its other end to bell crank 16 to be reciprocated by the cam which

operates said bell crank. The fingers 4 will normally tend to drop by gravity into engagement with the cigars, and, if desired, this movement may be assisted by a spring.

The operation of the device thus described, therefore, is as follows:

Assuming the parts to be in the position shown in the drawing, the next movement will be that of finger 9 which will drop, the bars 3 having previously been lowered, and then the bars and finger 9 will be moved toward the left, while the cigar in position B is moved to position A. At this point the bars 3 are elevated in front beneath the next cigar, the finger 9 having been elevated in front of the next cigar during the movement to the left, and after reaching the limit of their movement to the left, move upwardly and to the right to carry the next cigar to feeding position. Meanwhile bar 62 has dropped this elevating finger 4 and permitted fingers 4^a to drop out of contact with the cigar which it has carried to banding position, and with the fingers thus spread apart, the carriage moves toward the right until fingers 4 and 4^a are above and below the cigar in feeding position. At this point bar 62 rises to lift fingers 4^a into engagement with the bottom surface of the cigar in feeding position and permit fingers 4 to drop into engagement with the upper surface of the cigar in feeding position, so that the parts are again in the position shown in the drawing and the operation is repeated.

The adjusting mechanism.

The link 30, operated from the lever 94, is given a certain throw by cam 32, said link 30 being connected to shaft 29, and hence transmitting the throw to cam 26 and gripper block 60 and gripper bar 62. This movement is always constant and is the distance from B to A. As has been described, on the movement of gage finger 9 to the left, said finger comes up slightly in advance of the next cigar which is to be moved to feeding position and upon continued movement to the left engages said next cigar and thereafter, when the feeding mechanism operates toward the right, the feeding bars and gage, together with the cigar with which the gage contacts, are brought to the feeding position. The gage finger 9 will, without adjustment, always occupy the position shown when in extreme right position, so that it is obvious that if a cigar one-half the size of the one shown were to be fed, said cigar would have its axis, instead of on the line B, half way between line B and the finger 9. When, now, the gripper head moves the distance equal to the distance from B to A, the axis of the cigar at A will be as much to the left of A as it was to the left of B. Since it is essential that the

cigar should be properly positioned at the banding machine, for otherwise the band would not be properly applied, some adjustment must be made whereby the axis of 5 the cigar, no matter what its width, will always be, when in feeding position, upon the line B, so that when the gripper head moves the distance from B to A, its axis, when moved to banding position, will always be 10 upon the line A, and therefore in the proper, effective banding position. Therefore, mechanism is provided for adjusting the extreme right position of gage finger 9 toward the right or toward the left, depending upon 15 whether a wider or narrower cigar is to be fed, so that, with the gage finger in its position furthest toward the right, the axis of the cigar will be upon line B. For this purpose there is provided the adjusting 20 mechanism 110 which comprises means for varying the inclination of cam 26, for obviously this degree of inclination determines the amount of throw to the right of the gage finger. An operating handle 116, pivoted at 115 upon a bracket 111, depending from hub 27, is formed integrally therewith, an arm 118 engaging in the forked end of the pivoted lever 52, said lever being pivoted at 53 in the hub 27 which is fixed to 25 the end of shaft 29, pivotal axis 53 having fixed at its other end the cam 26. Obviously, by rotating the handle 116, cam 26 will be rotated to provide greater or lesser inclination and hence greater or lesser throw 30 of the feed bars and gage 9 to the right. An index plate 119 may be provided with index numerals 120 and with openings 121 into which a spring detent 117, carried by arm 116, may extend. It is only necessary 35 to adjust the movement of feed bars 3 and gage finger 9 to the right, since, as we have seen, in its left movement, the cam roller 25 leaves the cam 26 and the gage finger 9 is free to swing into engagement with the 40 next cigar regardless of its width. By this adjustment, therefore, it will be seen that if a narrower cigar is to be fed, the gage finger is adjusted to move so that its extreme right position is nearer the axis B by the desired amount; in other words, its throw to the right is diminished. If a wider cigar is to be fed, the gage finger is adjusted 45 so that its extreme right position is further away from the axis B, that is, the throw to the right is increased. 50 Since the gripping fingers 4 and 4^a grip the cigar in feeding position preparatory to transferring it to banding position, it will be seen that if a narrower cigar is employed 55 than the one shown, for example, not only will the first cigar be positioned between fingers 4 and 4^a, but said fingers will also overlap the second cigar and may drag two 60 cigars therewith toward the banding position. It is, therefore, apparent that when the gage finger 9 is adjusted for a wider or narrower cigar, it is necessary also to adjust the extreme left positions of fingers 4 and 4^a, that is, if the extreme right position of gage finger 9 is moved nearer the axis B for a thinner cigar, the extreme left position of gripping fingers 4 and 4^a must be moved toward the right, so that the ends thereof also approach the axis B; that is, 70 the distance from the ends of the gripper fingers 4 and 4^a, and gage finger 9 is reduced to substantially the new width of the cigar, or increased, as the case may be. To accomplish this the gripper head carrying the 75 gripper fingers 4 and 4^a is not fixed to the shaft 29 but is slidably mounted thereon and is connected thereto, as we have seen, by the link 51. Said link is connected at one end to the gripper head 60 and at the other 80 end to the lever 52, so that as adjustment is made by handle 116 to move the extreme right position of the gage finger 9 toward or away from the axis B, the gripper head will be operated in the reverse direction, 85 that is, if the gage finger 9 is moved toward the left by this adjustment, the gripper head is moved toward the right, and vice versa. The gripper head is prevented from rotating about shaft 29 by means of a downwardly extending straddle member 130, 90 adapted to straddle fixed shaft 131. 95 The entire machine can be driven from any suitable source of power, as by a motor, either directly or from a suitable belting to 100 drive the shaft 40 which carries cam 37. Said shaft may be geared to the shaft 95 which carries the cams 32 and 92 at the rear of the machine, so that all of the cams will be operated in unison, thus ensuring proper 105 timing. 110 Suitable springs 100, 101, 102 may be provided for normally holding bell cranks 7 and 16 and link 94 in effective engagement with their cams. 115 Throughout this specification I have described my invention in connection with a cigar feeding and banding mechanism, but I wish it distinctly understood that this was solely for illustrative purposes and to describe one practical embodiment of my invention, and that the invention herein is capable of a wide variety of uses on other articles. Thus, for example, the device can be utilized in connection with candy wrapping or banding machinery or generally with any type of wrapping or banding machine wherein a plurality of similar articles are fed to a banding or wrapping machine and then discharged. 120 125 The subject matter of this application is disclosed in my co-pending application, Serial No. 640,463, filed May 21, 1923. In accordance with the provisions of the patent statutes, I have described the prin- 130

5 ciple of my invention together with the apparatus which I now consider to represent a practical embodiment thereof, but I desire it understood that my invention is not confined to the particular form of apparatus herein shown and described, the same being merely illustrative, and that the invention can be carried out in other ways without departing from the spirit of my invention, 10 and therefore, I claim broadly the right to employ all equivalent instrumentalities coming within the scope of the appended claims, and by means of which objects of my invention are attained, and the new results 15 accomplished, as herein set forth, as it is obvious that the particular embodiment herein shown and described are only some of many that can be employed to attain these objects and accomplish these results.

20 Having described my invention, what I claim and desire to secure by Letters Patent is:

25 1. In a device of the character described, means for feeding a plurality of cigars one at a time to feeding position, and means for adjusting said first named means corresponding to various sized cigars.

30 2. In a device of the character described, reciprocable means for feeding a plurality of cigars one at a time to feeding position, and means for adjusting the throw of said reciprocable means in feeding direction corresponding to various sized cigars.

35 3. In a device of the character described, reciprocable means for feeding a plurality of cigars one at a time to feeding position, reciprocable means for gaging the cigars in feeding position, and means for adjusting the throw of said reciprocable means in 40 feeding direction corresponding to various sized cigars.

45 4. In a device of the character described, means for feeding a plurality of articles to feeding position, means for actuating said first named means, means for adjusting said last named means to vary the extent of operation of said feeding means, said last named means comprising a cam, and means for varying the inclination of said cam.

50 5. In a device of the character described, means for feeding a plurality of articles one at a time to feeding position, means adapted to move toward feeding position to gage the article in feeding position preparatory to moving said article to operating position, and means for simultaneously adjusting the extent of movement of said first two means toward feeding position corresponding to various sized articles.

55 6. In a device of the character described, means for feeding a plurality of articles one at a time to feeding position, means for adjusting said first named means to vary the extent of movement thereof toward feeding position, gripping fingers adapted to engage

the article in feeding position and move it to operating position, and means for regulating the movement of said fingers with respect to the article in feeding position simultaneous with the adjustment of said first named means.

7. In a device of the character described, means for feeding a plurality of articles one at a time to feeding position, means for adjusting said first named means to vary the extent of movement thereof toward feeding position, gripping fingers adapted to engage the article in feeding position and move it to operating position, means for adjusting the position of said fingers relative to the article in feeding position, and a single operating member for both of said adjusting means.

8. In a combined cigar feeding and banding machine, means for feeding a plurality of cigars one at a time to feeding position, means adapted to move toward feeding position to engage the cigar in feeding position preparatory to moving said cigar to banding position, and means for adjusting the extent of movement toward feeding position of said first two means corresponding to cigars of various thicknesses.

9. In a combined cigar feeding and banding machine, means for feeding a plurality of cigars one at a time to feeding position, means adapted to move toward feeding position to engage the cigar in feeding position preparatory to moving said cigar to banding position, and means for decreasing the extent of movement toward feeding position of said first two means corresponding to cigars of lesser thickness and increasing the extent of said movement corresponding to cigars of greater thickness.

10. In a combined cigar feeding and banding machine, means for feeding a plurality of cigars one at a time to feeding position, means adapted to move toward feeding position to engage the cigar in feeding position preparatory to moving said cigar to banding position, means for decreasing the extent of movement toward feeding position of said first two means corresponding to cigars of lesser thickness and increasing the extent of said movement corresponding to cigars of greater thickness, and manually operable means for operating both adjustments simultaneously.

11. In a combined cigar feeding and banding machine, reciprocable means for feeding a plurality of cigars one at a time to feeding position, reciprocable means adapted to move the cigar in feeding position to banding position, and means for adjusting the limit of throw of both of said reciprocable means toward feeding position corresponding to cigars of various thicknesses.

12. In a combined cigar feeding and banding machine, means for feeding a plurality of cigars one at a time to feeding position,

gripping fingers adapted to engage the cigar in feeding position and move it to banding position, and means for adjusting the position of said fingers relative to the cigar in feeding position.

13. In a combined cigar feeding and banding machine, means for feeding a plurality of cigars one at a time to feeding position, gripping fingers adapted to engage the cigar in feeding position and move it to banding position, and means for adjusting the extent of movement toward feeding position of said fingers corresponding to various thicknesses of cigars.

14. In a combined cigar feeding and banding machine, means for feeding a plurality of cigars one at a time to feeding position, gripping fingers adapted to engage the cigar in feeding position and move it to banding position, and means for decreasing the extent of movement toward feeding position of said fingers corresponding to a thinner cigar and increasing said movement for a thicker cigar.

15. In a combined cigar feeding and banding machine, means for feeding a plurality of cigars one at a time to feeding position, means for adjusting said first named means to vary the extent of movement thereof toward feeding position, gripping fingers adapted to engage the cigar in feeding position and move it to banding position, and means for adjusting the position of said fingers relative to the cigar in feeding position.

16. In a combined cigar feeding and banding machine, means for feeding a plurality of cigars one at a time to feeding position, means for adjusting said first named means to vary the extent of movement thereof toward feeding position, gripping fingers adapted to engage the cigar in feeding position and move it to banding position, and means for adjusting the position of said fingers relative to the cigar in feeding position.

17. In a combined cigar feeding and banding machine, means for feeding a plurality of cigars one at a time to feeding position, means for adjusting said first named means to vary the extent of movement thereof toward feeding position, gripping fingers adapted to engage the cigar in feeding position and move it to banding position, means for adjusting the position

of said fingers relative to the cigar in feeding position, and a single operating member for both of said adjusting means.

18. In a device of the character described, a conveyor, means for imparting to said conveyor elliptical motion, said conveyor being adapted on its upward movement to raise a plurality of articles from a stationary platform and to deposit the same in an advanced position on said platform the width of one of said articles, means for regulating the distance of advance of said conveyor, means associated with said first means to impart an elliptical motion to a finger which will raise said finger in advance of an oncoming article and retract the finger to position said article at a predetermined point, means independent of said imparting means for imposing a lag upon the downward movement of said finger and means associated with said regulatory means adapted to vary the distance of retraction of said finger.

19. In a device of the character described, a conveyor, means for imparting to said conveyor elliptical motion, said conveyor being adapted on its upward movement to raise a plurality of articles from a stationary platform and to deposit the same in an advanced position on said platform the width of one of said articles, means for regulating the distance of advance of said conveyor, means associated with said first means to impart an elliptical motion to a finger which will raise said finger in advance of an oncoming article and retract the finger to position said article at a predetermined point, means independent of said imparting means for imposing a lag upon the downward movement of said finger, means associated with said regulatory means adapted to vary the distance of retraction of said finger, means comprising a pair of vertically operable jaws adapted to be reciprocated in a horizontal plane and to grasp the article in the said predetermined position and to advance it into a second predetermined position, means being provided to vary the amplitude of the horizontal movement of the jaws, as and for the purpose described.

This specification signed this 7 day of May, 1923.

FRANCIS X. MALOCSAY.
